UNITED STATES PATENT OFFICE.

ADELBERT A. THOMAS, OF CHICAGO, ILLINOIS, ASSIGNOR TO CRESCO MANUFACTURING CO., OF CHICAGO, ILLINOIS, A CORPORATION OF ILLINOIS.

MACHINE FOR COVERING METALLIC BOXES.

1,377,231.

Specification of Letters Patent.

Patented May 10, 1921.

Application filed September 26, 1918. Serial No. 255,803.

To all whom it may concern:

Be it known that I, ADELBERT A. THOMAS, a citizen of the United States, and a resident of Chicago, in the county of Cook and State 5 of Illinois, have invented certain new and useful Improvements in Machines for Covering Metallic Boxes, of which the following is a full, clear, and exact description.

The invention relates to machines for covering metallic boxes.

One object of the invention is to provide an improved machine for covering boxes which is simple in construction and by which the covering may be lapped and held around 15 the edge of the box.

A further object of the invention is to provide a machine for this purpose which is simple in construction and efficient in operation.

20 The invention consists in the several novel features hereinafter set forth and more particularly defined by claims at the conclusion hereof.

In the drawings: Figure 1 is a side elevation of a machine embodying the invention. 25 Fig. 2 is a vertical section. Fig. 2^a is a detail section showing the dies in the relative position assumed when the covering has been applied to the outside of the box. Fig. 2^b is 30 a detail view showing the upper die with the folders holding the covering lapped under the edges of the box. Fig. 2^c is a detail section showing the dies in relative position assumed when the covering has been completely secured to the box. Fig. 3 is a plan 35 and Fig. 4 is a vertical transverse section of the transversely movable lower dies. Fig. 5 is a plan, parts being shown in section, of the upper die. Fig. 6 is a section taken on line 6—6 of Fig. 2. Fig. 7 is a section taken 40 on line 7—7 of Fig. 6.

The invention is illustrated as applied to a machine with a supporting frame 10 which is adapted to be secured to a work-table 11 in any suitable manner. This frame comprises a base 12 which is adapted to support a guide 13 in which the die-carrier 14 is transversely slidable to alternately bring the holding dies and the presser die for applying the covering to the inner sides of the box into operative position beneath the upper die. The frame also comprises a standard 15 having formed therein a guide-way 16 in which a stem 17 for operating the upper

die is vertically slidable. This stem is held 55 in the guide-way 16 by a front plate 18.

A holder block 20 shaped to fit into the box to be covered is fixed to a post 19 which is fixed in the transversely reciprocable carrier 14. This block is removably secured to 60 the post 19 by screws 20' to facilitate the change of forms for different boxes.

Block 20 conforms substantially to the shape of the inside of the box, so that the latter can be placed over and will be held 65 around the block. This block is provided with kerfs 23 to receive the usual inwardly projecting hinge-lugs on the box. A cover holder member 24 surrounds the block 20, is formed with an opening 25 which has its 70 sides properly spaced from the block so that the sides of the box can be dropped onto the block, and the top surface of this member is provided with a gage 24' to support a sheet 26 of suitable covering material of the 75 desired shape necessary to cover the box. A bottom plate 27 is secured to member 24. Posts 28 extend downwardly through and are vertically movable in openings 27' in the carrier 14. The plate 27 is extended to underlie the block 20 to limit the upward movement of the holder member relatively to the block, so that normally the upper surface of holder member 24 will be disposed substantially flush with the top of a box on 80 block 20. Springs 29 between plate 27 and carrier 14 press the cover-holder member 24 upward into normal position shown in Fig. 2, to permit the holder member to recede as the upper die forces the cover around the 90 sides of the box on the block.

Adjacent the other end of the carrier 14 is mounted a post 21 which carries a suitable presser block and box stripper. The carrier 14 is transversely reciprocable so that the 95 blocks 20, 21 may be alternately brought into coöperative relation with the upper vertically reciprocating die. Suitable stop pins 22 are secured on the guide plate 13 and a coacting stop 22' is secured to the top of the 100 carrier 14. The latter stop, when in engagement with one of the stops 22, will position the carrier beneath the upper member.

A presser block 71 of suitable form, to press the portions of the cover which have 105 been lapped around the box-edges against the inner sides of the box, is fixed to the upper end of post 21. A box stripper member

72 having an opening around said head is provided with posts 73 which are vertically slidable in the carrier 14 and a bottom plate 75. Said member is held normally raised by 5 springs 74 which are disposed between the bottom plate 75 of member 72 and the carrier 14. Plate 75 is extended to underlie a portion of the plunger 21 to limit the upward movement of said member relatively 10 to the plunger. When the upper die member containing the box and infolded cover is lowered, it will engage the stripper member 72 and force it downwardly below the presser-block 71 and the latter will enter the 15 box and force the cover so that its cemented face will adhere to the inner sides of the box as shown in Fig. 2^a. When the upper die member is raised, the stripper member 72 will engage the edge of the covered box and force 20 it off the block 71 and cause it to remain in the upper die.

A spring pressure device which is adapted to provide cumulative pressure or force to the cover holder member 24 when the said holder is lowered and like pressure to stripper member 72, when the members are forced downwardly by the upper die, comprises a rod 80, having its upper end fixed in the guide-way 13, a spring 81 around said 30 rod and engaging an adjustable nut 82 adjacent the lower end of said rod, a circular plate 83 engaged by the upper end of the spring and vertically slidable on depending posts 84, and having studs 85 projecting 35 from the upper face thereof into openings 86 in the guide-way 13 so that when either the guide-posts 28 for the cover holder member 24 or the guide posts 73 for the stripper member 72 are lowered, spring 81 will be compressed to store sufficient force to positively 40 lift either of said members and more particularly to provide sufficient force to strip the covered box from the presser-member 71.

The upper die comprises a plate 32, a body 45 33 and a bottom plate 34 all secured together, and to the lower end of stem 17. An opening 35 is formed in the plate 34 and body 33 which is shaped to conform to the sides of the box with the cover around it. 50 A plunger 37 conforming to the shape of the top of the box is slidably mounted in the opening 35 so that the covered box in said opening may be ejected from the upper die thereby. The upper die is adapted, when 55 operated in conjunction with block 20 and holder-member 24, to fold the cover sheet into the shape shown in Fig. 2^a. During this folding operation, plate 34 will engage the spring-pressed holder member 24 60 and force it downwardly against the force of springs 29 and spring 81 to permit the upper die to force the cover around the box, as shown in Fig. 2^a.

A series of in-folders 38 are radially slid- 65 able in the body 33 and their inner ends con-

form normally to the form of the opening 35 and to the box. These are adapted to engage the cover to lap the marginal portions inwardly under the edge of the box as shown in Fig. 2^b, and are conjointly operable by a 70 ring 39 which is rotatably held in an annular groove 33' in body 33 and has pins 41 secured therein (Fig. 7) which engage cam-slots 40 in the folders respectively. A handle 42 is secured to ring 39 to facilitate the 75 manual operation of the ring and a spring 43 is applied to the handle to retract it and normally hold the folders 38 retracted or inoperative. A slideable latch 44 which is pressed inwardly by a spring 50, is adapted 80 to enter a notch 45 in the ring 39 to normally lock the ring so that the in-folders will retain the cover lapped around the edge of the box as shown in Fig. 2^b, until the upper die member is again lowered to press the 85 cover against the inside of the box. This latch will be automatically released while the upper die is being lowered by a trip-bar 46 which is fixed to the guide-plate 13 and has an inclined upper edge 47 adapted to 90 engage the rear edge of a slot 48 in latch 44. The bar 46 passes through a guide-lug 49 which is fixed to the body 33. As a result, it is not necessary for the operator to hold the in-folders and they will remain 95 operative and hold the cover until they are automatically released by the operation of the upper die.

The stem 17 may be operated by any suitable mechanism, as exemplified by a lever 51 100 which is pivoted to the standard 10, at 52 and has its front end extended in a slot in the stem, a link 53 and a treadle 54. An adjustable stop screw 55 at the upper end of the stem 17 is adapted to engage the standard 15 105 to limit the downward movement of the upper die member.

A stem 56 is secured to the ejector member 37 and is slidably held in the stem 17. A spring 57 is applied to hold member 37 normally at the top of opening 35 in member 33. Stem 56 and member 37 are adapted to be operated relatively to the body 33 and stem 17 by a suitable lever 58 which is pivotally supported at 59 on plate 18 and has 110 its inner end formed so it may be swung inwardly to engage the upper end of stem 56 and operate plunger 37. By lifting the lever 58 which is normally outside of the stem, the member 37 may be operated to eject the covered-box from the opening 35, which occurs 115 after the box has been completely covered as hereinafter set forth.

The under side of the cover sheet 26 has a 120 suitable cement applied thereto which becomes adhesive when it is heated and suitable electric heaters 70 are disposed in the body 33 to heat the upper die member so that when the cover has been laid around the outside of the box, it will adhere thereto. 130

In operation, assuming the carrier 14 to be in position shown in Fig. 4 of the drawings, a box will be placed on the block 20 and a covering sheet 26 will be laid on the member 24 as shown in Fig. 2. Next, the treadle 54 will be operated to lower the upper die member which will cause the cover sheet to be laid around the outside of the box and forced into position shown in Fig. 2^a, the member 24 being forced downwardly away from the block 20 by the plate 34 of the upper die member. During the retraction of the upper die member, the operator will shift handle 42 to conjointly force the folders 38 inwardly as shown in Fig. 2^b. During this retraction, the box and cover will remain in opening 35 of the upper die member. Next, the carrier 14 will be shifted to the left to bring the presser block 71 into operative position below the upper die member and the latter will then be lowered which will cause the presser block 71 to force the cover against the inside of the box, as shown in Fig. 2^c. The operator can place another box on the block 20 while the upper die member is being operated in connection with the presser block 71. This cycle of operations may be continued indefinitely.

In operation, the carrier 14 will initially be placed in the position shown in Fig. 4 of the drawings and a metallic box to be covered will be placed on the block 20. A covering sheet with cemented face downward will be placed on the holder member 24 and will be properly positioned thereon by the gage 24'. The treadle 54 will then be operated to lower the upper die. Plate 34 will engage the cover sheet 26 on the holder 24 and stretch it around the box on the block 20 simultaneously forcing the holder 24 downwardly against the force of springs 29 and 81 until the cover is folded into the position shown in Fig. 2^a. Next, the treadle will be released and spring 90 will retract the upper die member, the box and cover remaining in the member 33. The operator will then shift handle 42 forwardly against the force of spring 43 to cause ring 39 to force the in-folders 38 inwardly into the position shown in Fig. 2^b. These folders will be held in such position, because the latch 44 will lock the ring 39 against retraction and, therefore, the cover will be held with portions thereof lapped under the edge of the box, as shown in said figure. Next, the operator will shift the carrier 14 transversely to the left to bring the presser block 71 and stripper 72 into operative position below the upper die member. The treadle 54 will be

again operated to lower the upper die member. Before the presser block 71 passes into the box in the upper die member, trip 46 will release latch 44 so that the in-folders will be retracted to permit the presser block 71 to pass into the box. During this lowering movement of the upper die, the plate 34 will engage the stripper member 72 and force it downwardly in advance of the upper die, while the presser block engages the inturned portion of the cover and forces it firmly into engagement with the inside of the box, so that the cover will adhere to the box as shown in Fig. 2^c. When the treadle is released, the stripper member 72 acted on by spring 81 and spring 74 will engage the edge of the box and strip it from the presser block 71, to cause the box to remain in the upper die. The lever 58 will then be operated to cause plunger 37 to eject the covered box from the upper die. During the pressing operation, the operator can place another box on the block 20. When the carrier 14 is shifted transversely to the right, the machine will be in readiness for a like cycle of operations.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a machine of the character described, the combination of coöperating die-members for pressing a cover on a box, of transversely movable in-folders, means for conjointly operating said in-folders, automatic means to lock the in-folders in operative position and means for releasing the locking means.

2. In a machine of the character described, the combination of coöperating die-members for pressing a cover on a box, of transversely movable in-folders, means for conjointly operating said in-folders, means for locking the in-folders in operative position, and automatic means for releasing the locking means.

3. In a machine of the character described, the combination of coöperating die-members for pressing a cover on a box, of transversely movable in-folders, a ring for conjointly operating said in-folders, means for locking the ring, and means for automatically releasing the ring.

ADELBERT A. THOMAS.
